United States Patent Office.

GEORGE K. SNOW, OF WATERTOWN, MASSACHUSETTS.

Letters Patent No. 90,599, dated May 25, 1869.

IMPROVEMENT IN PAPER CUFFS.

The Schedule referred to in these Letters Patent and making part of the same.

To all whom it may concern:

Be it known that I, GEORGE K. SNOW, of Watertown, in the State of Massachusetts, have invented a new and useful Wristband, or Cuff; and I do hereby declare the following, when taken in connection with the accompanying drawing, to be a full and exact description of the same.

My invention is an improvement in the class of wristbands, or cuffs, which are cut from paper or some stiff material resembling paper, and relates to the button holes.

It consists in combining two button-holes of different shapes in the same wristband, so that the wristband may be fastened by a stud, or unfastened, with great facility, when upon the wrist of the wearer, while, at the same time, there is no danger of losing the stud.

In making my wristband, I cut one hole substantially to the shape represented at A, in the drawing. The other I cut substantially to the shape represented at B.

The hole at A is the hole most commonly found in paper wrist bands. It is a button-hole of safety, for the stud, and if of proper size, cannot be detached without applying considerable force to bend the stiff material of the cuff. But if this button-hole will not permit the stud to become detached through accident, it will not allow it to be easily removed by design.

The hole at B, on the contrary, allows the stud to be easily detached. The neck of the stud is placed in the part *a* of the button-hole, when the smaller plate of the stud can be slipped through the remaining long and narrow part with very little bending of the paper or other material. The stud, however, is liable to slip from this button-hole by accident.

The button-hole at B, as well as the button-hole at A, is not new in itself. Wristbands are made with both holes like the hole shown at B. But while such wristbands are easily fastened and unfastened, they are also extremely liable to lose the stud.

So wristbands are made with both button-holes like the one at A. Such wristbands do not lose the stud, but they are buttoned and unbuttoned with difficulty.

By my combination of these two holes, in the same wristband, I obtain what is required, viz., a wristband

which can be readily fastened or unfastened when upon the wrist of the wearer, and which, at the same time, will not render the stud liable to be lost.

The two holes are in the usual position of the button-holes of a wristband; that is, at corners opposite to each other, across the long side of the cuff.

It is advisable, both for safety and facility in fastening and unfastening, that the holes should be cut, in reference to each other and the other parts of the cuff, as shown in the drawing, where the hole represented at A is cut lengthwise with the cuff, and the hole represented at B is cut with the part *a* towards the corner of the cuff.

To fasten a wristband, containing my invention, the smaller plate of the stud is passed first through the button-hole A, and then through the button-hole B. This brings the hole at A on the outside of the fastened cuff, which is always necessary. The stud can then be easily slipped in and out the hole B, while the hole A holds it fast.

It will be found advantageous to so cut the button-holes, that the wristbands may be considered rights and lefts. It is sufficiently indicated, in the drawing, how the holes should be cut for this purpose. The side of the cuff there represented is to be considered as the side to be in view when upon the wrist of the wearer.

When my invention is applied to a reversible wristband, or cuff, it is best to cut the second pair of button-holes in the places represented in the drawing; that is, reversible cuffs should have, in each end, two holes which are alike. The button-holes not used with the stud will be used to attach the wristband, or cuff to the sleeve. When a reversible wristband, which has been worn, is reversed, the hand should be changed. This gives the advantage of rights and lefts.

What I claim, and desire to secure by Letters Patent, is—

A wristband, containing two button-holes of different shapes, substantially as and for the purposes specified.

The above specification of my said invention, signed and witnessed at Boston, this 12th day of March, A. D., 1869.
